UNITED STATES PATENT OFFICE.

PAWEL BOCHENEK, OF BROOKLYN, NEW YORK.

CHANGE-HANDLER.

1,141,759.

Specification of Letters Patent. Patented June 1, 1915.

Application filed May 29, 1914. Serial No. 841,906.

To all whom it may concern:

Be it known that I, PAWEL BOCHENEK, a citizen of the United States, residing at Brooklyn, in the county of Kings and State 5 of New York, have invented new and useful Improvements in Change-Handlers, of which the following is a specification.

The invention relates to a coin delivering device, and more particularly to the class of 10 change handlers.

The primary object of the invention is the provision of a device of this character wherein change will be automatically delivered into the hand of a person, thereby obviating the necessity of picking up the said change from a counter or other support, which requires time and inconvenience to the 15 person.

Another object of the invention is the provision of a device of this character wherein the change is supported upon a shutter or disk which covers an opening in the top of the said device so that on manipulating a delivery funnel the shutter or disk will swing 20 to a position for dropping the coin or coins within the funnel whereby the said coin or coins will fall directly into the hands of the manipulator of the device thereby enabling the quick handling of the change and insuring 25 a convenient mode of receiving the same.

A further object of the invention is the provision of a device of this character which is simple in construction, automatic in operation, thoroughly reliable and efficient in its 30 purpose, and inexpensive in manufacture.

Other objects will be in part obvious and in part hereinafter pointed out.

The invention accordingly consists in the construction, combination of elements and 40 arrangement of parts which will be exemplified in the construction hereinafter pointed out, and the scope of the application of which will be indicated in the appended claims.

In the drawings:—Figure 1 is a top plan view of the device constructed in accordance 45 with the invention. Fig. 2 is a side elevation thereof. Fig. 3 is a view similar to Fig. 1 with the casing broken away. Fig. 4 is a 50 vertical longitudinal sectional view showing the parts shifted. Fig. 5 is a vertical transverse sectional view on the line 5—5 of Fig.

1. Fig. 6 is a plan view of a modified form of cover plate or top.

Similar reference characters indicate corresponding parts throughout the several views in the drawings.

Referring to the drawings in detail, the change handling device comprises a base 10 from which rises spaced vertical legs or uprights 11 which support an elliptical shaped horizontally disposed hollow body or casing 12, it being understood of course that the body or casing may be of any other desirable shape and made from any suitable material, having formed in its top a circular opening 13, while integral with and projecting from the inner faces of opposite sides of the said casing are bearings 14 and 15 respectively, which support the change handling mechanism hereinafter fully described.

Swingingly connected to the bearing 14 is the extension or arm 16 of a change delivery funnel 17 having a discharge spout 18 through which change is delivered into the hand of a person after being deposited within the funnel 17, the arm 16 thereof being connected to the bearing 14 by means of a pivot 19 which is passed through the said 65 arm and engaged in the bearing. Swingingly connected to the bearing 15 is a rocking lever 20 which is formed near opposite ends with elongated slots 21 and 22 respectively, the slot 21 being designed to receive a 70 pin or lug 23 mounted in the end of an extension 24 provided on the funnel 17, while the slot 22 is designed to receive a pin or lug 75 mounted in and depending from a circular shaped shutter or disk 26 which is disposed directly beneath the top of the casing 12 and is adapted to normally close the opening 13 therein. The shutter or disk 26 is formed with opposed guides 27 which 80 slidably fit upon spaced parallel guide rods 28 having their ends engaged in the casing 12 at opposite points thereof, the funnel 17 being formed with a cut away portion 29 to permit the passage of the lever 20 during 85 swinging movement thereof.

Integral with the rim or side wall of the casing 12 at opposite sides of and spaced from the bearing 15 are stop ears 30 which are arranged in the path of movement of one 90 95 100

end of the lever 20 to limit the swinging movement thereof. The lever 20 is connected to the bearing 15 by means of a pivot 31 which is passed through the lever and engaged in the said bearing.

Connected to the casing 12 at one side of the funnel 17, and also connected to the said funnel is a coiled retractile spring 32 which is designed to hold the funnel near one end 10 of the casing 12 and thus sustain the shutter or disk 26 in normal position for closing the opening 13 in the casing.

The top 33 of the casing 12 is detachably mounted thereon so that it can be removed 15 to give access to the delivery mechanism of the device should the occasion require.

In the operation of the device the change or coins to be delivered to a person are placed on the shutter or disk 26, the opening 20 13 in the casing 12 being provided for this purpose. Now, the person to receive the change places his or her hand upon the spout 18 of the funnel 17 with the palm upward and covering the spout. On exerting a forward pull upon the funnel 17 the latter swings on the bearing 14, and during this movement the shutter or disk 26 swings rearwardly or in the reverse direction, causing the coins or change to be discharged into the 25 funnel 17, which delivers the said coins or change into the hand of the person, thereby obviating the necessity of picking up the change or coins from a counter or other support when the same are placed thereon as usual. It will be apparent that the device 30 will automatically deliver the coins or change to a person in a single operation of the device. When the funnel 17 is released by the person the spring 32 acts thereon to move it to normal position, and during such movement the shutter or disk 26 is actuated for closing the opening 13 in the top of the casing 12 of the device so that the latter is set for repeating the operation thereof.

40 In Fig. 6 there is shown a slight modification of the cover plate or top wherein the same is constructed of a rectangular shaped portion 34 and a substantially semicircular shaped portion 35, said portion 34 being 45 formed with an upstanding marginal flange 36 serving as a guard to prevent the dropping of coins therefrom when placed upon the cover plate or top.

From the foregoing it is thought that the

construction and manner of operation of the 55 device will be clearly understood, and therefore a more extended explanation has been omitted.

What is claimed is:—

1. A change handling device comprising a 60 base having spaced upstanding legs opposite each other, a horizontally disposed hollow body supported by the legs in superposed relation to the base and having a circular opening, bearings formed interiorly of the 65 casing, an extension arm swingingly pivoted to one of the bearings, a discharge funnel supported by the arm, a rocking lever pivoted to the other bearing and having elongated slots near opposite ends, a lug on 70 the funnel and engageable in one of the slots in the lever, a shutter for normally closing the opening in the casing, a lug on the shutter and engaged with the other slot in the lever, spaced parallel guide rods mounted in 75 the casing at opposite sides of its opening, guide members integral with the shutter and slidably engaged on the rods, and means for tensioning the discharge funnel when pulled upon.

2. A change handling device comprising a 80 base having spaced upstanding legs opposite each other, a horizontally disposed hollow body supported by the legs in superposed relation to the base and having a circular 85 opening, bearings formed interiorly of the casing, an extension arm swingingly pivoted to one of the bearings, a discharge funnel supported by the arm, a rocking lever pivoted to the other bearing and having elongated slots near opposite ends, a lug on 90 the funnel and engageable in one of the slots in the lever, a shutter for normally closing the opening in the casing, a lug on the shutter and engaged with the other slot in the lever, spaced parallel guide rods mounted in the 95 casing at opposite sides of its opening, guide members integral with the shutter and slidably engaged on the rods, and a spring connected with one end of the casing and to the 100 discharge funnel.

In testimony whereof I affix my signature in presence of two witnesses.

PAWEL BOCHENEK.
